UNITED STATES PATENT OFFICE.

WARREN FUHRMANN, OF WESTFIELD, NEW JERSEY, ASSIGNOR TO THE MULTI-COUNTER MACHINE COMPANY, OF NEWARK, NEW JERSEY, A CORPORATION OF NEW JERSEY.

DESIGN FOR A REGISTER CASING.

Application filed December 19, 1925. Serial No. 15,790. Term of patent 14 years.

To all whom it may concern:

Be it known that I, WARREN FUHRMANN, a citizen of the United States, and a resident of Westfield, in the county of Union and State of New Jersey, have invented a new, original, and ornamental Design for a Register Casing, of which the following is a specification, reference being had to the accompanying drawing, forming part thereof.

In the drawing, the figure is a perspective view of the article, showing my new design.

What I claim is:—

The ornamental design for a register casing substantially as shown.

WARREN FUHRMANN.
